UNITED STATES PATENT OFFICE.

JOSEPH A. McCORMICK, OF CHICAGO, ILLINOIS, ASSIGNOR TO J. J. McLAUGHLIN, LIMITED, OF TORONTO, ONTARIO, CANADA, A CORPORATION OF ONTARIO.

SODA-WATER DRAFT ARM AND FAUCET.

1,295,541.

Specification of Letters Patent. Patented Feb. 25, 1919.

Application filed April 27, 1918. Serial No. 231,094.

To all whom it may concern:

Be it known that I, JOSEPH A. McCORMICK, a citizen of the United States, residing at Chicago, in the county of Cook and State 5 of Illinois, have invented a certain new, useful, and Improved Soda-Water Draft Arm and Faucet, of which the following is a full, clear, concise, and exact description, such as will enable those skilled in the art to make 10 and use the same.

My invention relates to improvements in faucets and has special reference to soda water draft faucets.

The object of my invention is to provide 15 a faucet whereby when the faucet is opened the initial movement of the handle shall result in a smooth stream of solid liquid at low pressure for quickly drawing the required quantity, and the further movement 20 of the handle shall result in the projection of a small stream of the liquid at high velocity for thoroughly mixing the previously drawn liquid and producing the desired effervescence.

25 My invention consists in a faucet of the kind described, provided with a valve controlled chamber connected to a supply of the liquid and provided with two delivery passages of respectively large and small area 30 and means whereby when the valve is first opened the delivery is through the large passage and wherein a further movement of the operating handle results in the closing of the large delivery passage, causing the liquid to 35 be delivered through the small passage.

My invention also consists in a soda water faucet having a large and a small delivery passage, a valve controlling the flow of liquid to both of said passages and means 40 for closing the large passage after the valve has been opened for shutting off the flow through the large passage and limiting the delivery to the small passage.

My invention also consists in the several 45 features of construction and in the combinations, relations and arrangements of devices and parts whereby I am enabled to attain the above mentioned and other objects, and all as hereinafter described and particularly 50 pointed out in the appended claims.

My invention will be more readily understood by reference to the accompanying drawing forming part of this specification and in which:

55 Figure 1 is a side elevation partly in sec-

tion, of a draft arm and faucet portraying a preferred embodiment of my invention;

Fig. 2 is a central vertical sectional view of the faucet on the line 2—2 of Fig. 1;

Fig. 3 is a detail horizontal section on the 60 line 3—3 of Fig. 1; and

Fig. 4 is a perspective view of the cam plate.

In the operation of drawing a glass of 65 soda water it is desirable to draw the glass three-quarters or seven-eighths full of the water without disturbing it to any appreciable extent, and thus preventing the effervescence thereof, then to project a small stream of the water at high velocity into the 70 glass to effect a thorough mixing of the contents and the violent effervescence of the water.

While faucets have been produced which 75 result in an approximation of the result desired, they have all been more or less complicated in construction and required various movements of the operating handle to produce the character of stream wanted.

By means of my improved faucet the operator automatically first produces a smooth solid stream of the water at low velocity for quickly filling the glass to the desired point, and then a further slight movement 80 of the handle produces the final small mixing stream at high velocity.

My improved soda water draft arm and faucet as shown in the drawings consists of a hollow stem 10 adapted for mounting on and connecting to a soda water fountain as 85 by the threaded pipe nipple 11. The stem carries the faucet proper 12 at its outer end. I preferably removably mount the faucet on the stem by the threaded connection 13. The stem and the faucet are provided with a central passage 14 for the flow of the liquid from the supply. The faucet shell or casing 15 is rigid with the stem and stationary. Within the casing 15 I provide a relatively 90 large central valve chamber 16 in communication with the supply passage 14 and provided with a valve seat 17 at its lower end, surrounding a central discharge passage 18.

The chamber 16 opens through the upper 95 end of the casing 15 and I close the upper end with a screw plug 19. Within the chamber 16 I provide a valve 20 for closing the discharge passage 18. This valve has an enlarged head 20, provided with a packing washer or disk 21 on its lower end secured 100 to the valve seat 17.

110

to the body of the valve by a central screw 22. I yieldingly hold the valve upon its seat by a helical compression spring 23 which surrounds a stem 24, upstanding from the valve 20, and finds a seat for its upper end within the plug 19.

The head 25 of the screw 22 is relatively thick and depends within the passage 18 and I make it conical, as shown, so that it will 10 tend to center the valve 20 should there be any tendency for the same to be forced sideways.

The passage 18 is relatively short and terminates in an enlarged nozzle or outlet 26 15 in the lower end of the body 15.

For lifting the valve 20 I provide a faucet handle or lever 27, which normally extends centrally above the faucet body. Its lower end is forked to straddle the faucet body. 20 The ends 28 of the forked handle are perforated to receive pivot pins 29 for pivotally mounting the handle on the body. These pins have cylindrical inner ends 30 which 25 slidingly fit within vertical guide slots 31 in the sides of the faucet body, which permits the handle to move up and down on the body.

I make the lower end of the body 40 cylindrical and mount thereon a nozzle extension 30 41, which I provide with diametrically disposed arms 42 projecting upward from its upper end and adapted to be arranged between the arms 28 of the handle and the body of the faucet. These arms 42 are provided with threaded openings 43 to receive and retain the pivot pins 29, which are correspondingly threaded for mounting therein.

The nozzle extension 41 terminates at its lower end in a discharge opening of relatively large size, and which is slightly contracted at its extreme end, being conical in form but free of any internal shoulders to disturb the liquid as it is discharged.

Within the large passage 26 in the lower 45 end of the faucet I arrange a valve 45, adapted to close the lower end of the passage 18, and I mount this valve upon a central cross bar 46 which I provide on the extension nozzle. For this purpose I provide a depending stem 47 on the valve 45, having a reduced lower end 48 which I force into a central opening provided in the cross bar 46. The shoulder 49 on the stem 47, places the valve 45 relatively to the bar 46 and I so 55 proportion the several parts that the valve 45 will seat to close the passage 18 upon being lifted about one-eighth of an inch.

For lifting the valve 20 I provide a central stem 50, its lower end secured in the 60 valve 45 and long enough to extend up into the passage 18 and contact with the lower end of the screw head 25. This stem has a shoulder 41' which serves to clamp the packing disk 52 upon the valve 45.

65 For lifting the nozzle extension 41 and

thus through the valve 45 and the stem 50, lifting the valve 20 to open it, I provide a cam surface 53 in a cam plate 54, mounted on the top of the closing plug 19 and immediately below the handle 27. I provide 70 the cam surfaces 53 in the separate plate 54, which is carried by the body of the faucet, so that I can make the cam plate of a different, and if desired of a harder metal than the body of the faucet. I preferably make 75 the cam plate 54 in the form of a disk and I provide a shallow socket 54' having a peripheral upstanding flange 54" for receiving and retaining the cam plate or disk 54. This separation of the cam plate from the top of 80 the faucet permits of easier manufacture and assembly as the cam plate is self alining with respect to the roller. This cam surface is in fact a double cam and is arranged longitudinally in relation to the stem 10, or transversely to the axis of the pivots 29, upon which the handle swings. For coöperation with the cam surface, I provide a cam roller 55, carried by the handle 27 and mounted for rotation upon a horizontal bearing pin 90. 56, secured in the handle. The roller 55 being separate from the body of the lever 27 can also be made of a different metal from the handle and I preferably make it also of steel so that these two wearing parts, 95 the roller and the cam, are relatively indestructible. The cam surface 53 is inclined upwardly both rearwardly and forwardly from the center of the faucet and in the normal position of the handle the roller 55 contacts with the lower part thereof. The handle 27 can swing back and forth over the body of the faucet on the pivots 29 and any movement from the central normal position will cause the roller 55 to travel up the inclined surface of the cam and lift the handle, the nozzle extension, and in consequence the valve 20, thus putting the delivery passages 18 and 26, in direct communication with the central valve chamber 16. It will 110 be clear that the farther the handle 27 is swung over within the limits of the device, the higher the parts will be lifted, until finally the valve 45 will close the lower end of the passage 18. As soon as the valve 20 115 is lifted from its seat, the water is free to flow through the passage 18, around the valve 45, through the passage 26 and the discharge nozzle. The passage 26 and the discharge nozzle are so large in relation to 120 the annular space within the passage 18 around the stem 50, that the initial high pressure of the water is eliminated and the water flows from the nozzle in a smooth, solid stream, at low velocity. 125

In the operation of the device, when the valve 45 is lifted far enough to close the lower end of the passage 18, the free flowing of the liquid in a large stream is terminated. This point is within the control of the opera- 130

tor, for he merely has to move the handle 27 far enough to effect the closing of the lower end of the passage 18.

Having filled a glass three-quarters or seven-eighths full of the water in a quiet state, it is now desired, as explained hereinbefore, to violently agitate the liquid and thus cause its rapid effervescence. To accomplish this purpose it is desired to provide a small stream of the liquid projected at high velocity, for which a small central discharge passage 57 is provided, extending through the lower end of the stem 47 and communicating at its upper end with the threaded opening which receives the lower end of the stem 50, and I provide a central passage 58, extending from the lower end of the stem 50 and terminating adjacent to the upper end of the stem in lateral openings 59, whereby when the valve 45 has closed the lower end of the passage 18, the water will be forced at high velocity through the lateral passages 59, the central passage 58 and the small delivery passage 57.

I have thus provided two passages for the water from the valve chamber 16, one around the valve 45, which is of relatively large area and is successively enlarged in area from its beginning to substantially its delivery end, and the other a relatively small passage which is reduced in area step by step from the beginning to its delivery end. The large passage results in such a reduction of pressure due to the enlarging area of the passage that the flow of the water, while rapid, is relatively slow and very smooth and does not disturb the water to the extent of causing it to effervesce, while on the other hand the small passage, which is reduced in area from its beginning to its delivery end, causes the water to be projected in a fine needle-like stream from the discharge passage 57, under substantially the initial pressure of the water, thus causing the efficient mixing and effervescence of the previously drawn water.

On account of the relatively high pressure of the supply of soda-water the main valve 20 is held to its seat with relatively great force, but by means of the multiplied leverage which I have provided, viz, the coöperating cam parts and the swinging lever 27 the operator is enabled to readily and easily open the valve 20 against the pressure of the soda-water in the valve chamber 16. Once the valve is open it can be easily raised, when desired to close the lower end of the passage 18, but the leverage is such that even with the tendency of the closing of the lower end of the passage 18 to increase the pressure within the faucet, the operator is easily enabled to hold the valve 45 closed and thus produce the small stream of water of high velocity, which is desired.

Preferably I provide a relatively large

ball on the free end of the handle lever 27 and I secure the ball upon the lever by means of a threaded stem 61 and a flange nut 62, providing the end of the lever with a spherical socket 63 in which to seat the ball.

76

It is sometimes desirable to reduce the area of the supply passage 14 and for this purpose I provide a screw plug or pin 64, mounted in a threaded opening 65, provided in the body of the faucet and having its inner end 66 projecting into the passage 44. I provide a recess 67 in the inner wall of the passage 14 to receive the end 66 of the pin 64, the recess 67 being slightly larger than the end of the pin, which prevents a complete shutting off of the passage 14. I provide the outer end of the pin 64 with a screw driver slot 68 for effecting this adjustment, and to prevent the escape of liquid around the pin through the opening 65, I provide a packing nut 69 and packing 70 surrounding the stem.

80

85

As many modifications of my invention will readily suggest themselves to one skilled in the art, I do not confine or limit my invention to the specific structure herein shown and described, except within the limits of the appended claims.

90

I claim:

1. In a soda water faucet, a delivery passage of relatively large area, a valve normally closing the inner end of said passage, a second valve independent of said first valve for controlling the outer end of said passage and normally open, means for closing the second valve upon its seat to close such passage and coöperating means for opening the normally closed valve in advance of closing the second valve, and a centrally disposed relatively small open delivery passage entering the space between said valves and successively reduced in area from its inlet to its discharge point.

95

2. In a soda water faucet, a central supply chamber, a delivery passage leading therfrom, successively enlarged in area from said chamber to the discharge end of said passage, a valve within said chamber for closing said passage, an enlarged nozzle communicating with said delivery passage, a second valve independent of said first valve within the nozzle for closing the outer end of said delivery passage, means for lifting said second valve to close said passage, a stem rising from the second valve and adapted to lift the first valve from its seat before the second valve reaches its seat, and a relatively small delivery passage through said second valve substantially continuously reduced in area from its inlet to its discharge, to cause the discharge of the water in a solid fine stream at high velocity when the second valve closes the lower end of the delivery passage.

100

105

110

115

120

125

3. In a soda water faucet, a main supply

130

- chamber having a delivery passage leading therefrom, a main valve in said chamber normally closing said passage, means yieldingly holding the valve closed, an extension 5 nozzle on the faucet body communicating with said passage and movable back and forth relatively to said valve, a second valve independent of said first valve carried by the extension nozzle for closing the outer 10 end of said passage, a stem rising from said second valve through said passage and adapted to engage the main valve to lift the same in advance of the closing of the second valve, a relatively small delivery passage 15 through said stem, reduced in area step by step from its inlet to its outlet and terminating in a needle-like discharge opening, and a swinging handle on said faucet for lifting said extension nozzle.
- 20 4. In a soda water faucet having a main valve within a supply chamber normally closing the discharge passage of the faucet, a member slidingly mounted on the lower end of the faucet surrounding the discharge 25 end thereof, means carried by said member independent of said valve and upstanding within the faucet for lifting said valve from its seat, a lever pivoted at its lower end to the upper end of said member and normally 30 extending above the faucet, a separable cam plate and a coöperating cam part on the faucet and lever respectively for effecting the lifting of the lever and said member upon the swinging of the lever from its normal central position.
5. In a soda water faucet having a main valve within a supply chamber, and controlling the discharge passage of the faucet, means yieldingly holding the valve upon its 40 seat, means for lifting the valve from its seat, comprising a member slidingly mounted on the lower end of the faucet surrounding the discharge nozzle thereof, a stem projecting upward in the faucet and contacting with said valve, a lever mounted on the faucet and pivotally connected with said member, means for guiding the pivoted ends of the lever and the member longitudinally on the faucet, a stationary cam surface on 45 the faucet, and a cam roller carried by the lever for coöperation therewith, whereby when the lever is swung in either direction from its normal mid-position, the member will be raised and the valve lifted from its seat.
- 55 6. In a faucet a main valve within a supply chamber for controlling the discharge passage of the faucet, means yieldingly holding the valve upon its seat, means for lifting the valve from its seat, comprising a member slidingly mounted on the end of the faucet surrounding the discharge nozzle thereof, a stem projecting upward in the faucet and contacting said valve, a lever mounted on the faucet and pivotally connected with said member, the body of the faucet having vertical slots for receiving parts carried by the upper end of said member for guiding said lever and said member longitudinally on the faucet and coöperating 70 cam means on the faucet and the lever adapted for lifting the lever and said member upon the movement of the lever.
7. In a faucet a main valve within a supply chamber for controlling the discharge passage of the faucet, means yieldingly holding the valve upon its seat, means for lifting the valve from its seat, comprising a member slidingly mounted on the lower end of the faucet surrounding the discharging nozzle 80 thereof, a stem projecting upward in the faucet and contacting with said valve, a lever mounted on said faucet, a cam surface on the faucet and a cam roller journaled in said lever for coöperation therewith, whereby movement of said lever will lift said valve from its seat.
8. In a faucet means for controlling the discharge passage thereof comprising a member slidingly mounted on said faucet, a lever mounted on the faucet, a cam plate which is formed separately from the faucet body secured on the faucet, said cam plate having a groove therein, said groove being inclined upwardly from the center of the 95 plate to the periphery thereof, and a cam roller mounted upon a shaft secured in said lever, said cam roller being adapted for co-operation with either of the inclined portions of said groove, whereby movement of said lever will lift said slidingly mounted member and thereby open the discharge passage of the faucet.
9. In a soda water faucet, a main valve within a supply chamber and controlling the 105 discharge passage of the faucet, a valve lifting member slidingly mounted on the nozzle of the faucet, a swinging lever having arms embracing the faucet body and pivotally connected to said member, the lever normally 110 standing vertically above the faucet, a separate cam plate carried by the upper part of the faucet body beneath said lever, and an anti-friction roller carried by said lever for coöperation with said cam plate for lifting 115 said valve when the lever is swung from its normal mid position.
10. In a soda water faucet, a main valve within the faucet for controlling the discharge of soda water therefrom, a member 120 slidingly mounted on the nozzle of the faucet and having a part projecting within the nozzle for lifting said valve from its seat, a lever mounted upon the upper part of the faucet and pivotally connected with said member to lift same, a cam roller carried by the lever, and a circular cam plate for co-operation therewith carried by the body of the faucet for lifting said valve when the lever is swung from its normal valve closed 125 position.
- 60 65 70 75 80 85 90 95 100 105 110 115 120 125 130

position, the body of the faucet having a circular flange embracing the circular cam plate.

11. In a faucet of the kind described having a valve within a chamber for controlling the discharge of liquid from the faucet, a member slideable on the nozzle of the faucet for opening said valve, a swinging lever extending above the faucet and having arms 5 embracing the upper part of the faucet for connection with said member, pins pivotally connecting the arms of said lever and said

member, the body of the faucet provided with vertical guide slots, the inner ends of said pins projecting into said guide slots for 15 guiding said member, and cam means between the lever and the upper end of said faucet for lifting said member to open said valve as the lever is swung from its normal valve closed position. 20

In witness whereof I hereunto subscribe my name this 25th day of April, A. D. 1918.

JOSEPH A. McCORMICK.
